 Norton Company, Worcester, Mass., a corpora-
 tion of Massachusetts

Application May 10, 1941, Serial No. 392,833

6 Claims. (Cl. 51—151)

The invention relates to honing apparatus especially for the finishing of piston rings. By the word "honing" I intend to include all grinding, abrading, lapping and polishing operations performed with the apparatus herein described.

One object of the invention is to provide a honing tool for piston rings or any other objects having a cylindrical surface to be polished, adapted to smooth them with a minimum of labor. Another object of the invention is to provide a readily renewable abrasive for finishing cylindrical objects. Another object of the invention is to provide a quick acting clamp to clamp sandpaper or abrasive cloth around a cylindrical object. Another object of the invention is to provide a holder for holding an abrasive coated sheet in cylindrical form for operation on a work piece. Other objects will be in part obvious or in part pointed out hereinafter.

The invention accordingly consists in the features of construction, combinations of elements, and arrangements of parts, all as will be illustratively described herein, and the scope of the application of which will be indicated in the following claims.

In the accompanying drawings illustrating one of many possible embodiments of the mechanical features of this invention,

Figure 1 is a view, partly in side elevation and partly in vertical section, of a reciprocating tool machine to which the invention has been applied;

Figure 2 is a cross sectional view taken on the line 2—2 of Figure 1, showing certain controls on an enlarged scale;

Figure 3 is a similar cross sectional view taken on the line 3—3 of Figure 1;

Figure 4 is a view, partly in plan and partly in section, along the line 4—4 of Figure 1, illustrating further controls;

Figure 5 is a view, partly in front elevation and partly in section, showing the same controls as are shown in Figure 4 but in a different position;

Figure 6 is a vertical sectional view of the lower stop disk;

Figure 7 is an elevation of the intermediate stop;

Figure 8 is a vertical sectional view of the striking dog in the form of a disk;

Figure 9 is a plan view of the honing apparatus of the invention;

Figure 10 is a perspective view of said apparatus; and

Figure 11 is a side elevation of the apparatus.

The invention is more particularly concerned

with a chuck for holding a piece of sandpaper or abrasive cloth in contact with an object to be polished, together with a mounting for the chuck and for the sandpaper or cloth and means for opening and closing the chuck rapidly and means for holding the paper smoothly on the inside of the chuck. For a full understanding of the invention, its use on a machine to impart relative reciprocation, preferably equipped with means for advancing and withdrawing the work holder, is disclosed. It will be understood, therefore, that the apparatus of the invention can be mounted on any suitable machine to effect the reciprocatory and rotary motions or either of them with or without the means for separating the parts, and that such machine may be manually controlled or automatic or semi-automatic and either the tool or the work piece may be reciprocated. Therefore, in order better to illustrate the application of the present invention, I shall now describe one form of machine tool to which the invention may be applied.

Referring now to Figure 1, the machine tool may have a base 10 and a column 11 merging into a horizontal overhead extension 12 ending in a forked portion 13. In the forked portion 13 are coaxial journals 14 mounting a splined shaft 15 for rotation and reciprocation. A pulley 17 is keyed to the splined shaft 15 and rotates it, permitting the splined shaft to reciprocate in the pulley. The pulley 17 fits between two parts of the fork 13 and is driven by a belt 18 running from a motor pulley 19 driven by a motor 20. Since the belt 18 changes its direction of travel, it runs over a pair of pulleys 20a mounted on a bracket 21 fastened to the upper part of the column 11.

The splined shaft 15 passes through the upper bearing 14 into a cylinder 22 and constitutes a piston rod, being connected by a thrust ball bearing 23 to a piston 24 in the cylinder 22. Next to the cylinder 22 and desirably formed out of the same casting is a valve cylinder 25. A valve rod 26 passes through the cylinder 25 and has thereon two valve members 28 and 29 forming valve chambers 31, 32 and 33. A pressure pipe 34 transmits fluid under pressure to the center of the valve cylinder 25 while exhaust pipes 35 are located symmetrically with respect to the pressure pipe 34.

The valve parts are shown in Figure 1 in the neutral or stop position with the valve members 28 and 29 blocking the entrance to channels 36 and 37 leading to opposite ends of the cylinder 22. When the valve members 28 and 29 are

moved upwardly, the chamber 32 connects the pipe 34 to the channel 36, and when they are moved downwardly the same chamber 32 connects the pipe 34 to the channel 37. It will also be seen that whichever channel 36 or 37 is not connected to the pressure pipe 34 must be connected to one of the exhaust pipes 35. It follows that raising the valve rod 26 from the position shown in Figure 1 admits pressure fluid to the upper end of the cylinder 22, and lowering of the valve rod 26 admits pressure fluid to the lower end of the cylinder 22 and whatever end of the cylinder 22 is not connected to pressure is always connected to exhaust. Therefore, the shaft 15 can be caused to move downwardly by raising the valve rod 26 and upwardly by lowering the valve rod 26.

Located upon the shaft 15 below the fork 13 is a striking disk 40 the diameter of which is great enough to overlap stop disks 41 and 42 on the valve rod 26. A stop arm 43 is located between the disks 41 and 42 and will or will not be struck by the disk 40, depending upon its angular position.

Fastened to the top of the rod 26 is an arm 45 mounting a roller 46 sometimes in position to contact a spring-pressed detent 47 urged to the left by spring 48 in a casing 49 fastened to the top of the cylinder 22. Referring to Figures 2 and 4, when a handle 50 affixed to the bottom of the valve rod 26 is turned to a certain position, the roller 46 as well as the stop arm 43 are out of the plane of the axes of the valve rod 26 and shaft 15 and away from the area in plan view of the detent 47 and the disk 40. Under such conditions the disk 40 will strike only one of the disks 41 or 42 and upon doing so will move the valve rod 26 until the valve members 28 and 29 have closed the entrances to the channels 36 and 37, whereupon the piston 24 will stop in the cylinder 22.

As shown in Figures 1, 6 and 7, the stop 43 has a spring striking member 51, and the stop disk 42 has an annular striking member 52 supported by springs 53. When either of these striking members is engaged by the disk 40, the spring or springs are compressed. When the resistance to movement is increased by the contact of the roller 46 with the detent 47, the spring or springs store up considerable energy which is given up when the resistance to movement decreases as it does when the roller 46 reaches the high point of the detent 47. Thus the spring 51 or the springs 53 push the valve rod 26 to carry the valve members 28 and 29 beyond the mid position, and the spring 48 back of the detent 47, once the roller 46 has passed the mid position on the detent 47, carries the valve member 26 still farther to reverse the valve. Thus the shaft 15 will always stop in the high position, but will reciprocate in the down position so long as the striking disk 40 is between the arm 43 and disk 42. By manipulating the handle 50, the operator can easily control the movement of the shaft 15 to make it reciprocate and, when desired, to withdraw to the upper or remote position and stop. The disks 41 and 42 and the arm 43 are preferably adjustable to any desired positions along the rod 26. In order to avoid friction and possible rotation of the rod 26 by the rotating disk 40 acting on the disk 41 etc., the disk 41 is preferably mounted on the shaft 15 through ball bearings 55.

Formed on the front of the column 11 is a slideway 60 upon which is mounted a vertically movable slide 61 supporting a table 62. The table 62 may be raised or lowered by means of a screw 63 mounted in a thrust bearing 64 in the machine base 10 and extending into a nut 65 on the under side of the table 62. The screw 63 can be turned by a hand wheel 66.

Considering now the apparatus which more specifically constitutes the present invention, on the upper side of the table 62 I secure in any suitable way a block 70. This may be merely such a large block that its own weight will prevent it from moving on the table 62. The block 70 has a T shaped groove 71 in which, as shown in Figure 11, fits a large head 72 of a bolt 73. As shown in Figures 9, 10 and 11, on the bolt 73 and near the opposite ends thereof are the hubs 74 of levers comprising front arms 75 and rear arms 76. The parts 74, 75, 76 may be formed in one piece, as shown. Also located on the bolt 73 and inside of the hub 74 are hubs 77 of levers comprising front arms 78 and rear arms 79. From the drawings it will be seen that the levers 75, 76 are on one side and the levers 78, 79 are on the other side of a vertical plane passing through the bolt 73. The arms 75 and 78 are bowed and are respectively attached to a pair of hollow semi-cylinders 80 and 81, respectively, as by means of a pair of bolts 82 extending through the arms 75 and to the semi-cylinder 80 and a pair of bolts 83 extending through the arms 78 and into the semi-cylinder 81.

Located between the hubs 77, 77 on the bolt 73 is a boss 85 formed on one end of a cylinder 86 containing a piston 87 connected by a piston rod 88 to a collar 89 located on a pin 90. Referring to Figures 9 and 10, a pair of links 91 extend from the outer ends of the pin 90 to a pin 92 passing through both of the links 91 and also through the outer ends of the two arms 76. Similarly a pair of links 93 are mounted on the pin 90 adjacent collar 89 and extend to a pin 95 upon which they are mounted and upon which also are mounted the outer ends of the arms 79.

As shown, the semi-cylinders 80 and 81 are contacting each other, jointly forming a perfect hollow cylinder. When, however, the piston 87 moves in the cylinder 86 to the left, the collar 89 moves the pin 90 outwardly and this swings the links 91 and 93 and causes the arms 76 and 79 to approach each other which swings the arms 75 and 78 away from each other, separating the semi-cylinders 80 and 81.

Referring to Figures 9 and 10, mounted on the outside of the semi-cylinder 80 is a bracket 100 and mounted on the outside of the semi-cylinder 81 is a bracket 101. Mounted on these brackets 100 and 101 are posts 102 and 103 upon which may be mounted rolls of sandpaper 104 and 105. The rolls 104 and 105 are, in fact, part of one continuous length of sandpaper identified by the numeral 106. One of the rolls 104 or 105 may be considered the let-off or feeding roll and the other thereof may be considered the take-up roll. The sandpaper 106, as shown, extends between the semi-cylinders 80 and 81 through both sides thereof and at the left-hand side loops around a post 107 formed on a bracket 108 fastened to the outside of one of the semi-cylinders, such as the semi-cylinder 80. As shown, the sandpaper 106 follows the inside contour of the semi-cylinders 80 and 81 very closely. The abrasive is on the 75 inside of the sheet.

For holding the sheet of sandpaper or other sheet abrasive material to the inside of the semi-cylinders 80 and 81, I provide vacuum means which may also be utilized to move the piston 87 in the cylinder 86. As shown in Figure 9, I may provide a motor 110 operating a vacuum pump 111 connected to a hollow cylinder 112 with a gauge 109. The pump 111 will substantially exhaust the cylinder 112 which represents stored energy. A valve casing 113 has in it a valve rod 114 and three valve pistons 115, 116 and 117. These pistons define chambers 118 and 119. A pipe 120 is connected to the cylinder 112 and has two branches 121 and 122 connected to the valve cylinder 113. The cylinder 86 is connected by pipes 123 and 124 to the valve cylinder 113. When the valve rod 114 is to the right, as shown, the chamber 118 connects the "storage" cylinder 112 to the right-hand end of the cylinder 86 and thus holds the piston 87 to the right. If the valve rod 114 is pushed to the left, the "storage" cylinder 112 will be connected to the pipe 123 and thereby the left-hand end of the cylinder 86, drawing the piston 87 to the left, moving the links 91 and 93, and separating the semi-cylinders 80 and 81. A pipe 125 is connected to the valve cylinder 113 opposite the branch 122 and with the valve rod 114 to the right, as shown. The chamber 119 connects the "storage" cylinder 112 to the pipe 125 which has branches 126 and 127 leading respectively to the semi-cylinders 80 and 81. The semi-cylinders 80 and 81 have interior chambers 130 and 131, respectively, connected to the pipes 126 and 127, respectively, and connected to the inside of the hollow cylinders by a great number of openings 135. The suction of air to the cylinder 112 and the pump 111 along pipes 126 and 127 and the pipe 125 from the chambers 130 and 131 through the openings 135 holds the abrasive paper 106 to the insides of the semi-cylinders 80 and 81 and what is more holds it smoothly in true cylindrical shape.

I have referred to the sheet 106 as sandpaper. It should be understood that any type of abrasive can be used, such as emery, corundum, fused alumina, silicon carbide, and any suitable adhesive such as glue, synthetic resin or varnish can be used to hold the abrasive to the paper. The paper itself may be of any desired variety and, furthermore, the backing may be cloth instead of paper, if desired. In the claims I shall refer to the element 106 as "sheet abrasive material" which is to be deemed to include further variations, such as where the backing is sheet metal, for example.

At the lower end of the shaft 15 is a suitable chuck or arbor 140 upon which may be mounted annular objects 141 to be finished. The machine is particularly designed to hone piston rings. However, any kind of a cylindrical member can be mounted upon the shaft 15 and honed with the apparatus of the invention.

The apparatus which is more particularly the subject of the invention is mounted upon the block 70 by means of the head 72 in the T slot 71. The bolt 73 may have an enlarged diameter portion 145 for supporting the weight of the parts and the various hubs 74, 77 and 85 can be held in place on the bolt 73 by means of a nut 146. The valve cylinder 113 may be conveniently mounted on the column 11 and the operator may move the valve rod 114 by means of a knob or handle 147. The pipes 123, 124, 125, 126 may be and preferably are bendable. The operator, after locating the semi-cylinders 80 and 81 axially

in line with the axis of the shaft 15, pushes the knob 147 to the left or inwardly and this causes the semi-cylinders 80 and 81 to fly apart and releases the sheet abrasive 106. The operator may then ascertain if an unused abrasive portion of the sheet abrasive material 106 is located in the semi-cylinders and, if not, may manipulate the rolls 104 and 105. It is noted that in order to insure movement of the piston 87 in the cylinder 86, a somewhat loose fit of the piston rod 88 in the head of the cylinder 86 is relied upon to admit air. An opening 150 may be provided at the other end of the cylinder 86 for the same purpose. The operator now moves the handle 50 upwardly which causes the chuck 140 to descend. As the disk 40 passes below the arm 43, he swings the handle 50 to move the arm 43 so that the disk 40 will contact it on the up stroke. The chuck 140 is now reciprocating in a lower range of positions. The operator can now pull the handle 147 which will suck the sheet abrasive 106 and close the semi-cylinders 80 and 81. It is preferred, however, to stop the chuck 140 in a downward position to be sure that no loop of sheet abrasive 106 is formed adjacent the entrance points before closing the semi-cylinders. If this is done the toggle action of the links 91, 93 serves to compress the semi-cylinders 80 and 81 firmly against the work and to move the whole apparatus slightly in the slot 71 either angularly around the bolt 73 or along the slot more accurately to align the parts. The handle 50 can then be moved up or down, as the case may be, to start the reciprocation. After a few minutes, the piston rings 141 have been honed and by simply swinging the handle 50 in one direction or the other, the chuck 140 is caused to rise and stop and by simply pulling the knob 147 the semi-cylinders are opened up readily for insertion of a new work piece or work pieces.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In apparatus of the class described, a pair of hollow partial cylinders which when joined constitute a substantially complete hollow cylinder, supply means for sheet abrasive material outside of said hollow cylinder including means for removing used material mounted to hold both sides of a loop of such sheet abrasive material into one joint between said pair of partial cylinders when said partial cylinders are closed, means also outside of said hollow cylinder around which the end of said loop of sheet abrasive material may be passed and positioned to hold said loop adjacent and allowing it to pass through the other joint between said pair of partial cylinders, chambers inside of each of said partial cylinders connected to holes extending to the inside surface of said hollow partial cylinders, vacuum means connected to said chambers, and means for clamping said hollow partial cylinders together and for separating them and unitary means for controlling said vacuum means and said clamping and separating means.
2. In apparatus of the class described, a base,

a bearing post slidingly supported on said base, bell crank levers rotatably mounted in opposed relation on said post, toggle means joining corresponding ends of said cranks, complementary cylindrical members mounted on the free ends of said cranks respectively and adapted when closed to form a space to receive a work piece, said semi-cylindrical member having ports communicating with their inner faces, means for guiding and supporting sheet abrasive material between said members in position to be engaged by negative pressure exerted through the ports of said members and to be held firmly thereby against the interior surface of said members, and means including a source of fluid pressure for moving said toggles to close and to separate said semi-cylindrical members and for simultaneously exerting negative pressure through said ports of said members.

3. In apparatus of the class described, a chuck having a T-shaped groove, an upright member slidingly supported in said groove, scissor-like levers rotatably mounted on said upright member, toggle means joining corresponding ends of said scissor-like levers, complementary semi-cylindrical members mounted on the free ends of said scissor-like levers respectively and adapted when closed to form a closure to receive a work piece to be abraded, said semi-cylindrical members having ports communicating with their inner faces, slidably mounted means for operating said toggle to close and to separate said semi-cylindrical members, means to actuate said toggle operating means and to exert negative pressure through the ports of said semi-cylindrical members when said toggle operating means is actuated to close said members, and lengths of sheet abrasive material extending between said members and adapted to be held against the inner surfaces of said members respectively thus forming a continuous abrading surface when negative pressure is exerted through the ports of said members.

4. In apparatus of the class described, a pair of complementary semi-cylindrical members having suction ports communicating with the interior surfaces of said members, a pair of scissor-like supporting arms connected at their free ends to said members, means for supporting said scissor-like members for rotation to close and to separate said members, means for actuating said arms to close and to separate said semi-cylindrical members, a source of negative pressure, conduits connecting said source of negative pressure to the said ports of the semi-cylindrical members and to said arms actuating means, control means for supplying negative pressure to

said ports simultaneously with pressure supplied to said arms actuating means to close said members, and for cutting off the supply of negative pressure to said ports while pressure is supplied to said arms actuating means to separate said members, and sheet abrasive material in position to be clamped to the inner surfaces of said members respectively by negative pressure supplied through the said ports thereof and to thus form a closed cylindrical interior abrasive surface, and a work holder reciprocable into and out of the space thus formed.

5. In apparatus of the class described, a pair of hollow partial cylinders which when joined constitute a substantially complete hollow cylinder, means for supporting said partial cylinders respectively to open and close them, means for actuating said supporting means, a supply of sheet abrasive material, means for guiding a loop of said material between said partial cylinders, means for exerting negative pressure on the inner surfaces of said partial cylinders to engage and hold said sheet abrasive material around the curved inner surfaces of said partial cylinders, and means for operating said means for exerting negative pressure in timed relation to said means for actuating the supporting means for said cylinders.

6. In apparatus of the class described, a plurality of complementary members presenting complementary concave faces grouped about a common axis, said members having chambers therein and each member having a plurality of ports in its concave face communicating with the chamber in the member, means mounting said members for movement of at least one of them in a direction toward or away from another to thereby contract said members relative to a round work-piece received therebetween for abrasive action or to expand them for the removal of the work-piece, tool means for performing an operation on the work-piece and comprising flexible sheet material resting against said faces and covering over the ports in the latter, means for creating in said chambers and hence in said ports a pressure below atmospheric so that atmospheric pressure holds the flexible sheet material conformed to and against the concave faces of said members during operation thereof upon the work-piece, means for controlling expansion and contraction of said members, and means for controlling the pressure in said chambers whereby conformity of the sheet material to said concave faces may be controlled for the reception or removal of the work-piece or operation thereon.

HERBERT S. INDGE.
